UNITED STATES PATENT OFFICE.

ABRAHAM L. LEFEVER, OF LANCASTER, PENNSYLVANIA.

RAILWAY PASSENGER-COACH WATER-CLOSET ATTACHMENT.

SPECIFICATION forming part of Letters Patent No. 782,973, dated February 21, 1905.

Application filed June 21, 1904. Serial No. 213,472.

To all whom it may concern:

Be it known that I, ABRAHAM L. LEFEVER, a citizen of the United States, residing at Lancaster, in the county of Lancaster and State 5 of Pennsylvania, have invented certain new and useful Improvements in Railway Passenger-Coach Water-Closet Attachments; and I do hereby declare the following to be a full, clear, and exact description of the invention, 10 such as will enable others skilled in the art to which it appertains to make and use the same.

This invention relates to improvements in a railway passenger-coach water-closet attachment of that class in which a concaved cup, bowl, or basin is arranged under the projecting end of the tubular conduit from the closet bowl or seat within the body of the car to the desired point underneath the bottom thereof and pivoted or hinged to said projecting end and adapted to close or cover the same when the coach is stopped at a station and to be opened or uncovered when said coach is under way after leaving said station.

The object of the invention is to provide 25 means whereby water-closets in passenger-coaches may be used during the stoppage of trains without fear or risk of dropping deposits in the closet-seat bowls onto the floor-planking or track-rails of such stations, thus 30 avoiding the closing and locking of the doors of the closets to prevent their being used during said stoppages.

The elements of the invention will severally and at large appear in the following description, and they will be separately or combinedly pointed out or set forth in the appended claim.

The purposes of the invention are attained by the mechanism, devices, and means illustrated in the accompanying drawings, similar reference characters designating like parts throughout the several views, in which—

Figure 1 is a side elevation of one end portion of a railroad passenger car or coach embodying the elements of the invention, with a portion of the side broken away, showing the interior of a water-closet with certain of said elements in place therein; Fig. 2, an enlarged top view of said portion of said coach with 45 full and dotted lines, showing said elements

in normally closed positions; Fig. 3, an inverted view of Fig. 2, showing the elements underneath the bottom of the coach in normally closed and opened position; Fig. 4, an enlarged sectional view taken through the center of the closet discharge-tube, showing the elements in said last-mentioned positions in direct elevation; and Figs. 5 and 6, respectively, are direct and completed top views of the drip-receiving cup and the discharge-tube as they appear when detached from Fig. 4.

Within the closet is arranged the usual seat-bowl A, covered by the usual seat-board a and top-lid a', both being hinged in place in the usual way, and through its bottom the bowl is provided with the usual drain pipe or conduit A', projecting the required distance through the bottom of the coach and having at its lower end a side projecting lug a², provided with a horizontal-bearing orifice through which is passed a headed pivot pin or rod a³. At the lower end of the conduit A' is arranged a concaved cup, bowl, or basin A², having at its open end side projecting ears a⁴ a⁴, provided with orifices through which said rod a³ serves to pivot said basin A² in place, so as to swing up over the mouth of said conduit to gather the droppings therefrom, being best shown by full lines in Fig. 4, and to swing away from said mouth to empty said droppings, being best shown by dotted lines also in Fig. 4, while one of said ears a⁴ is provided with an upwardly and outwardly sloping arm a⁵, whereby said basin is swung in either direction—that is, either up or down—into the respective positions above mentioned.

Extending vertically through the body of the coach from a prescribed point above its roof to the required distance below its bottom is mounted a rotatable rod B. With one end rigidly secured to the upper end of this rod above said roof and its other or free end outwardly extended toward the marginal edge thereof is a wing or blade b, adapted to be 90 swung in either direction by contact of air-currents thereagainst according to the running movement of the coach rotating said rod, and to the lower end of the rod below said bottom is rigidly secured the rear or inner end of 95 100

a crank or lever arm b' , being turned conformably to the rotation of said rod, said lever-arm having vertically through its free end an orifice for pivoting thereto one end of a link-rod B' , with its other end pivoted to near the outer end of the upwardly and outwardly sloping arm a' of the basin, said link-rod being adapted to trip or turn said basin to the dotted position indicated in the drawings 5 on rotation of said lever-arm b' , while a coiled spring B^2 , having one end pivotally connected with the outer end of said arm a' and its other end upheld by a post b^2 , projected from the bottom of the coach, serves through the 10 resiliency thereof to return said basin from the dotted to the full-line position, again covering the outlet end of the drain-tube A' or again placing it in the position to gather the droppings from said tube, as well as returning 15 all of the elements to the first or normally closed positions.

Now these several parts hereinbefore described and occupying the respective positions indicated in the drawings an inspection thereof 20 clearly shows that when the coach is standing still, as at a station, with the wing b at the upper end of the rod B and extending outwardly across the roof of the coach toward the outer edge thereof, with the lever-arm b' at the lower 25 end of said rod, the bowl A^2 covering the outlet end of the drain-tube A' , and the link-rod B' connecting said lever-arm and bowl, all being held in the full-line positions shown 30 through the contraction of the springs B^2 , said bowl is held in the position to gather and hold the droppings from said tube; that when the coach is moving away from the station in the direction of the arrow 1 the air-current caused 35 by the moving coach in coming in contact with the wing b will turn said wing in the direction of the curved arrow 2, and when said coach attains its full speed or headway said air-current will bring said wing to the dotted 40 position 3, rotating the rod B , turning the lever-arm b' to the dotted position 4, and thereby tilting or tripping said bowl to the dotted 45 position 5, discharging its contents; that the same remarks will hold true when the coach is moving in the direction of the arrow 6, except 50 that the wing b will move in the direction of the curved arrow 7, and when it has

attained to the position lying opposite to the dotted position 3, above mentioned, the lever-arm b' will be in the dotted position 8 and the bowl A^2 tripped or turned to the same dotted 55 position 5, in which position the bowl will be held by the air-currents against said wing while the coach is in motion and again returned to the full-line or closed position through the resilient action of the spring B^2 when the coach 60 again stops at a station.

The invention having thus been ascertained and described and the manner in which its functions are performed fully shown and set forth, what is considered new, and desired to 65 be secured by Letters Patent, is—

In a railway passenger-coach water-closet attachment, in combination; a seat-bowl arranged within the closet; a drain-tube arranged through the bottom of said bowl and projected through the bottom of the coach; a concaved basin arranged to cover the projected end of said tube and to be tilted away therefrom, said basin being hinged at one side to a side lug of said end; a coiled spring with 70 one end secured to the bottom of the coach and its other end pivoted to an upwardly-sloping arm of the basin, holding it in said covering position; a revoluble rod arranged vertically through the body of the coach, with 75 one end extending above its roof and the other end below its bottom; a lever-arm with one end rigidly secured to the lower end of said rod and the other end thereof extended toward the upwardly-sloping arm of said basin; 80 a link-rod with one end pivoted to the free end of said lever-arm and the other end thereof pivoted to the upper end of said upwardly-sloping arm; and a wing with one end rigidly secured to the upper end of said revoluble 85 rod above the roof of the coach, and the other end of said wing extending across said roof toward the side edge thereof; all substantially 90 as described and for the purpose hereinbefore set forth.

95 In testimony whereof I affix my signature in presence of two witnesses.

ABRAHAM L. LEFEVER.
